UNITED STATES PATENT OFFICE

JAMES SELVA, OF LAURELTON, NEW YORK

TAP PLATE FOR DANCING SHOES

Application filed December 17, 1931. Serial No. 581,573.

This invention relates to improvements in shoes and has particular reference to a tap plate for dancing shoes.

In the art of tap dancing, it has become the practice to tap with the edge of the sole of the shoe adjacent its tip, in addition to the usual method of striking the floor with the front portion of the bottom of said sole. Tap plates heretofore used only cover said front portion so that when the edge of the sole is employed to tap, the plate does not contact the floor, with the result that a different sound is produced and considerable wear is occasioned on the sole and upper of the shoe.

An object of the present invention is to overcome the above-mentioned drawbacks by providing a plate having a portion which engages over the edge of the sole of a shoe so that it can be utilized to strike the floor and at the same time protect the covered portion of the sole and the part of the shoe upper adjacent thereto.

The above and other objects will appear more clearly from the following detailed description, when taken in connection with the accompanying drawing, which illustrates a preferred embodiment of the inventive idea.

In the drawing—

Figure 1 is a perspective view of a shoe showing the invention applied thereto;

Figure 2 is a bottom plan view of the tap plate constructed in accordance with the invention;

Figure 3 is a top plan view thereof; and

Figure 4 is a fragmentary longitudinal section taken through the shoe, showing the plate applied thereto.

The invention is illustrated in its application to the toe portion of a shoe, but it will be understood, of course, that the plate, by slightly altering its shape, may also be constructed for application to the heel of said shoe and, in this connection, wherever in the following description reference is made to the "sole" of the shoe, this term is intended to also include the heel.

Referring more particularly to the drawing, the numeral 5 indicates a shoe which may be constructed particularly for dancing pur-

poses and which is provided with the usual sole 6.

The tap plate, which includes the essential feature of the invention, is made of any suitable light metal and comprises a body portion 7 shaped to conform substantially to the contour of the forward end or tip portion of the sole 6 and is secured thereto by suitable fasteners 8 extending through a plurality of apertures 9 formed in the plate. Along the edge of the body portion 7 adjacent the edge of the sole 6, the plate is provided with a laterally extending flange 10, preferably having its greatest width at the tip end of the sole and gradually tapering rearwardly toward the back of the plate. Adjacent the point of greatest width of the flange, the same is wider than the thickness of the sole 6 so as to fully cover that portion of its edge along which the flange extends, and also cover the portion of the tip of the shoe upper adjacent said sole. Thus, when a dancing step is employed in which the edge of the sole and tip of the shoe would ordinarily be used to strike the floor or dancing surface, the flange 10 instead comes in contact with said surface and thereby produces the same sound as when the body portion of the plate is tapped, and further protects the edge of the sole and tip of the shoe upper against excessive wear.

What is claimed is:

1. A tap plate for dancing shoes formed of light metal and comprising a relatively flat body portion adapted to be connected to and substantially only cover that portion of the sole of the shoe beneath the toes and having a concavity at its rear end, and a peripheral substantially vertical flange projecting upwardly from the front and side edges of said body of the shoe to which the plate is secured, said flange being of a depth or height at said front end greater than the thickness of the sole of the dancing shoe to which it is adapted to be applied, and being adapted to engage the edge of the sole at the sides, the height of said flange and the thickness of said body gradually decreasing rearwardly from the tip of the plate.

2. A tap plate for dancing shoes formed of

light metal and comprising a relatively flat body portion adapted to be connected to and substantially only cover that portion of the sole of the shoe beneath the toes and having 5 a concavity at its rear end and a peripheral substantially vertical flange projecting upwardly from the front and side edges of said body, said flange being of a height at said front end of the plate greater than the thickness of the sole of the dancing shoe to which 10 it is adapted to be applied and being adapted to engage the edge of the sole at the sides, said flange having a forward portion diverging slightly forwardly from the vertical at 11 the front edge of the plate so as to leave an open space for resonant purposes between the toe of the shoe and the flange when the plate is attached to the shoe.

20 In testimony whereof, I have affixed my signature.

JAMES SELVA.
